PANEL CREASE PULLER

Edmund A. Zielinski, 14 1st Ave., New York, N.Y.

Filed Jan. 16, 1959, Ser. No. 54,201

Term of patent 14 years

(Cl. D54—13)

Fig. 1 is a side elevational view of a panel crease puller showing my new design, the opposite side thereof being substantially the same in appearance;

Fig. 2 is a section taken on the line 2—2 of Fig. 1;
Fig. 3 is a section taken on the line 3—3 of Fig. 1; and
Fig. 4 is an elevational view of the upper right end of Fig. 1.

I claim:

The ornamental design for a panel crease puller, as shown,
